UNITED STATES PATENT OFFICE

JOHN F. GRACE, OF ARLINGTON, NEW JERSEY, ASSIGNOR TO WORTHINGTON PUMP AND MACHINERY CORPORATION, OF NEW YORK, N. Y., A CORPORATION OF VIRGINIA

SURFACE CONDENSER WATER-CIRCULATION SYSTEM

Application filed August 3, 1926. Serial No. 126,771.

This invention relates to surface condensers of the type used in power plant systems and more particularly to a system of water circulation whereby the direction of flow of the cooling water through the condenser may be 5 reversed when desired.

In condenser systems other than the pure water type débris, algæ, other growths and foreign material collect against the tube heads at the entrance to the tubes and interfere with the flow of the cooling water 10 through the condenser, thereby affecting the efficiency of the condenser.

It is an object of the present invention to 15 provide a condenser system in which the accumulated débris, growths, etc. may be removed from the tube heads without requiring the shutting down of operation of the condenser and the time and expense contingent 20 with such stoppage and the removal of the débris, by providing a structure wherein the direction of flow of the cooling water through the condenser may be reversed and will wash the débris and growths away from the tube 25 head.

With these objects in view, the invention consists in various features of construction and combination of parts, which will be first described in connection with the accompanying 30 drawings, showing a surface condenser water circulation system of the preferred form embodying the invention, and the features forming the invention will be specifically pointed out in the claims.

In the drawings—

Figure 1 is a view partly in side elevation and partly in section of one form of the improved condenser system.

Figure 2 is a view partly in side elevation and partly in section of another form of the condenser system.

Referring more particularly to the drawings, 1 indicates a surface type condenser which includes a plurality of tubes 3 through 45 which cooling water is circulated for facilitating the condensing of steam within the condenser and in the normal and usual operation of the condenser the cooling water is pumped from the intake channel 4 by a pump 5 which is illustrated in the drawings as a

motor operated pump driven by the motor 6. The motor 6 has reversed terminal connections 7 by means of which the direction of rotation of the motor 6 may be controlled. The pump 5 draws the water from the channel 4 upwardly through the nozzle 8 in the direction indicated by the solid line arrow A and discharges it into an intake water box 9 of the condenser 1. The water is forced through the tubes 3 of the condenser 1 and discharged out of the normal discharge water box 10 through the outlet pipe 11 into the discharge channel 12. A movable or traveling screen 13 is positioned in the intake channel 4 for screening débris and foreign matter 55 from the water prior to its entrance into the pump; however, particles of débris pass through the screen and are pumped by the pump into the condenser. Such débris and algæ and other growths accumulate on the 60 tube head 14 of the condenser as shown at 15 and interfere with the flow of the cooling water through the tubes, and consequently with the efficiency of the condenser. The 65 pump 5 is preferably of a screw propeller or other type by which the direction of flow of water can be reversed by reversing the direction of rotation of the impeller of the pump and thus by reversing the motor 6 through the reversed terminal connections 7 the direction 70 of rotation of the impeller 16 of the pump 5 may be reversed which will reverse the direction of flow of water through the condenser, taking the water from what is 75 normally the discharge channel 12 up through the pipe 11 and into the condenser at the top and downwardly through the tubes 3 into and through the pump, which direction of flow is indicated by the dot and dash arrows B. By reversing the direction of flow of 80 water through the condenser the débris, algæ and other growths will be washed from what is normally the inlets of the tubes 3 and from the tube head 14 and will be passed through 85 the pump 5 into the normal intake channel 4. In Figure 1 of the drawings a priming pump or air exhauster 20 is illustrated, the operation of which is controlled through a float 90 structure 21.

A screen 17 of any approved construction may be positioned in the channel 12.

In Figure 2 of the drawings, a modified form of the condenser system is illustrated in which the circulating pump 30 is on the normal discharge side of the condenser 31 and in this construction, the particular object is to prevent the corrosion of the tubes 32, tube heads 33 and analogous parts such as fer-
10 rules, by air, which has been separated from the water in eddy currents when the water has traveled at high speed in the pump or piping and also to keep away from the condenser tubes any air entering the circulation system
15 through leaky pump stuffing boxes and joints when the water pressure in the pump is below atmospheric pressure, which is a common condition during periods of low water level. The normal circulation of water through the
20 modified form of the water circulating system for condensers is from the intake channel 34 upwardly through the nozzle 35, through the water box 36 and into and through the tubes 32 of the condenser. After
25 passing through the tubes 32 of the condenser 31 the water passes through the intake pipe 37 of the pump structure 30 and is discharged by the pump into the channel 38. Webs 39 are positioned at the mouth of the nozzle 35
30 and are crossed preferably at 90° angles so as to prevent formation of a vortex in the water as it enters the condenser. A stream line grating 40 is shown beneath the working space of the condenser. Should débris and growth ac-
35 cumulate on the head 33 and normal inlets of the tubes 32 of the condenser 31, the direction of rotation of the impeller 41 of the pump 30 may be reversed by reversing the motor 42 through the medium of the reversed terminal
40 connections 43 which will force the water into the condenser 31 at the top and outwardly through the condenser and nozzle 35 into the channel 34. A priming pump or air exhaust-
45 er 45 is shown associated with the modified form of condenser system and its operation is controlled by the float 46.

It will be understood that the invention is not to be limited to the specific construction or arrangement of parts shown but that these
50 may be modified widely within the invention defined by the claims.

What is claimed is:

1. The combination with a steam condenser, of a circulating pump for forcing cooling water through the condenser, means for operating said pump and means for reversing the direction of operation of the pump for reversing the flow of water through the condenser.
- 60 2. The combination with a condenser, of a water circulating pump of such type as to permit reversing of direction of operation of its propeller for reversing the flow of water through the pump whereby the direction of flow of cooling water through the

condenser may be reversed for removing accumulating débris, and growths from the tube head of the condenser.

3. The combination with a condenser, of a water circulating pump of such type as to permit reversing of direction of operation of its propeller for reversing the flow of water through the pump whereby the direction of flow of cooling water through the condenser may be reversed for removing accumulating débris, and growths from the tube head of the condenser, and means for preventing a vortex in the water at its entrance to the condenser system.

4. In a condenser system, inlet and discharge water channels, a condenser, a pump for drawing water from one of said channels and forcing it through said condenser into the other channel, said pump being of the type whereby direction of rotation of its impeller may be reversed for reversing the direction of flow of water through the pump and condenser.

5. In a condenser system, inlet and discharge water channels, a condenser, a pump for drawing water from one of said channels and forcing it through said condenser into the other channel, said pump being of the type whereby direction of rotation of its impeller may be reversed for reversing the direction of flow of water through the pump and condenser, and screens in said channels.

In testimony whereof I affix my signature.
